APPARATUS FOR TREATMENT OF METAL

Carl M. Yoder, Lakewood, and Paul J. Abel, Cleveland, Ohio, assignors to The Yoder Company, Cleveland, Ohio, a corporation of Ohio

Application July 27, 1936, Serial No. 92,788

4 Claims. (Cl. 80—3)

This invention relates to apparatus for and process of operating on sheet metal stock, wherein it is fed to and between a pair or pairs of cutters to cut or slit the stock into longitudinal strips or sections, the edges of the strips or sections conditioned, trimmed or finished ready for subsequent treatment, and then, by preference, the strips or sections wound into a coil or coils, whereby they may be handled or transported.

5 The apparatus is adapted for operating on sheet metal stock that is hot or cold rolled and of varying width, thickness and length.

10 The apparatus is adapted for operating on sheet metal stock that is hot or cold rolled and of varying width, thickness and length.

One object of the invention is to provide an improved apparatus of this character that is 15 relatively simple in construction and has large capacity.

Another object of the invention is to provide an apparatus of the type shown in the co-pending application filed April 15, 1935, by Carl M. 20 Yoder, one of the petitioners herein, Serial No. 16,373, Patent 2,179,461, November 7, 1939, but embodying improvements therein whereby the apparatus is materially simplified and reduced in size and cost of manufacture and large capacity maintained.

Another object of the invention is to construct an improved apparatus of this type and process wherein provision is made for rolling down the trimmed edges of the sheet metal sections.

30 Another object of the invention is to provide an improved machine for edging or conditioning relatively narrow metallic strips.

A further object of the invention is to provide an improved process of edging or conditioning metallic strips of varying predetermined widths in rapid manner.

Other objects of the invention will be apparent to those skilled in the art to which our 40 invention relates from the following description taken in connection with the accompanying drawings, wherein

Fig. 1 is a plan view of an apparatus embodying our invention.

45 Fig. 2 is a side elevation.

Fig. 3 is a section on the line 3—3 of Fig. 1, enlarged.

Fig. 4 is a section on the line 4—4 of Fig. 3.

50 Fig. 5 is a section on the line 5—5 of Fig. 4.

Fig. 6 is a fragmentary view of parts shown in Fig. 5, enlarged; parts being in section.

Fig. 7 is a fragmentary section on the line 7—7 of Fig. 6.

Fig. 8 is a fragmentary section on the line 8—8

of Fig. 9, illustrating a modified form of construction.

Fig. 9 is a fragmentary section on the line 9—9 of Fig. 8.

Fig. 10 is a section on the line 10—10 of Fig. 11. 5

Fig. 11 is a section on the line 11—11 of Fig. 10.

Fig. 12 is a section on the line 12—12 of Fig. 11.

Fig. 13 is a detail view.

Fig. 14 is a section on the line 14—14 of Fig. 15.

Fig. 15 is a section on the line 15—15 of Fig. 14. 10

Figs. 16 and 17 are fragmentary views of parts shown in Fig. 15, enlarged.

Figs. 17a and 17b are fragmentary sectional views of metal strips illustrating two different forms of treatment to the edges thereof.

15

In the drawings, 1 indicates as an entirety a mechanism and the driving means therefor for trimming the opposite edges of the sheet metal stock A and cutting or slitting it into longitudinal strips or sections a; 2 indicates as an entirety a set of stock feed rolls and the driving means therefor; 3 indicates as an entirety a mechanism for guiding and edging, conditioning or up-setting the opposite edges of the strips or sections; 4 indicates as an entirety a mechanism for rolling down the conditioned or up-set edges of the strips; and 5 indicates as an entirety a mechanism for coiling the strips and the driving means for such mechanism.

Of the trimming and slitting mechanism 1, 6 30 indicates a support having standards 7 in which are mounted upper and lower shafts. The shafts in turn carry pairs or sets of cutters 7', the outermost pairs serving to trim the opposite edges of

the material and the intermediate pairs or sets 35 of cutters serving to cut the stock into strips or sections each of any predetermined width dependent upon the spacing of the adjoining pairs or sets of cutters 7'. As shown in Figs. 1 and 2, the stock A is disposed horizontally and delivered from a coil (not shown) such for example, as illustrated in the aforesaid application Serial No. 16,373. The mechanism 1 preferably includes feed rolls 8, 9, arranged forwardly and rearwardly of the pairs of cutters 7'. The shafts for the cutters 7' and feed rolls 8, 9, are driven through suitable gearing in a casing 10, and speed reducing means 11 from a motor 12. The parts above referred to are preferably substantially similar to that shown in the aforesaid application to which reference may be made for further illustration and disclosure thereof; it being understood that in the present application no claim is made to the form of trimming and slitting mechanism and that any desired con-

35

40

45

50

55

struction of such mechanism may be used. The material trimmed off by the outer pairs or sets of cutters is preferably guided downwardly as shown at *a'* to a scrap-cutting mechanism (not shown) which may also be of the construction shown in said application.

The feed mechanism 2 and the rolling down mechanism 4 are preferably substantially equally spaced forwardly and rearwardly of the guiding 10 and conditioning mechanism 3 for the reason that in passing through the latter mechanism the strips *a* are flexed or turned from a common horizontal plane, in which they pass through the feed mechanism 2, to vertical positions in 15 side by side substantially parallel relation and then flexed or turned back to a common horizontal plane by the mechanism 4 for guiding and feeding to the coiling mechanism 5. This arrangement permits the strips *a* to be flexed or 20 turned to their vertical positions for engagement with the guiding devices and edging, conditioning or up-setting rolls and flexed or turned back to normal position without affecting the feeding of the strips or their relation to each other in 25 passing through the mechanism 2 and mechanism 4.

The mechanism 2 is mounted on a frame 13, which by preference also supports the mechanisms 3 and 4. The mechanism 2 comprises the following: 14 indicates standards formed with seats for bearing boxes 15 in which are suitably mounted upper and lower shafts 16. At one side the shafts 16 are driven through suitable speed reduction gearing within a casing 17, by a motor 35 18. Either or both of the standards 14 may be mounted on the frame 13 for adjustment transversely thereof. The bearing boxes for the upper shaft 16 may be raised and lowered by suitable means, operated by a hand wheel 19, to vary the 40 space between the shafts 16 according to the thickness of the strips *a*. The mechanism 2 and the driving means therefor may be of any desired construction and therefore it is not thought necessary to further illustrate and describe in 45 detail its parts.

The combined guiding and edging, conditioning or up-setting mechanism 3 consists of the means for engaging the opposite edges of the strips *a* to condition or up-set them and means 50 arranged forwardly and rearwardly of said means for guiding the strips into vertical side by side relation thereto and therefrom; that is, the guide means at the front and rear of the conditioning means co-operate to guide each strip into and 55 maintain it in a vertical plane while being engaged by the adjacent pairs of edging or conditioning elements 20.

The edging, conditioning or up-setting means consist of pairs of annular elements 20, one pair 60 for each strip, each element being formed with a groove 21 to receive the adjacent edge of a strip, the cross sectional shape of the groove corresponding to the shape, in cross section, desired to be imparted to or effected upon the edge 65 of the adjacent strip *a*, examples of such shapes being shown in Figs. 16, 17, 17a and 17b. As will be readily understood, the cross sectional shape of the longitudinal edges of each strip may be varied at will, dependent upon the ultimate 70 use or treatment of the strip. The opposite edges of each strip may be similarly or differently shaped and by preference both edges of each strip are acted on simultaneously, but the invention is not to be limited to such simultaneous operation. The conditioning means and

the guiding means are so mounted that relative transverse adjustment thereof may be effected, the latter means being in the present disclosure adjustable relative to the conditioning elements 20. As shown in Figs. 4, 5, 8 and 9 the elements 5 20 are removably mounted on upper and lower shafts 22, 23, respectively, and each is formed with a plurality of grooves 21 (preferably four grooves) each in alignment with a groove of the adjacent element 20 on the other shaft. Each 10 pair of related grooves may be of different cross sectional shape as compared to each of the remaining pairs of related grooves. That is, correspondingly positioned pairs of grooves formed in the respective adjacent elements are preferably of similar cross sectional shape so that when the strips are engaged and conditioned, they are uniformly spaced and the edges on all of the strips similarly edged. In this arrangement we may provide on the edges of the strips any one 20 of the cross sectional shapes formed by the pairs of related grooves 21, by adjustment of the guide means without adjustment or disassembly of the elements 20 or the mounting therefor. However, the invention is not to be so limited since, by 25 substitution of different edging elements, one or more strips *a* may be edged or conditioned differently from the remaining strips.

Referring to Figs. 1, 2, 3 and 4, 24, 25, indicate standards mounted on the support 13, one there- 30 of (standard 25) being movable laterally to an inoperative position (see dotted lines in Fig. 3), whereby the shafts 22, 23, may be assembled or disassembled and the edging elements may be removed and others assembled on the shafts. 35 When in operative position, the standards 24, 25, are secured to the support 13 by bolts 26, the support being formed with slots 27 to permit movement of the bolts, which secure the standard 25 in position, when the latter is moved laterally and a slot 28 for a lug 29 which depends from the latter standard (see Fig. 3). The lug 29 is threaded to receive a feed screw 30, which is rotated by a wheel 31. The outer end portion of the screw 30 is mounted in a suitable bearing 40 32 and provided at opposite sides thereof with collars 33 to prevent endwise movement of the screw 30 when turned to move the standard 25. The standards are formed with aligned openings 34 to receive bearing boxes 35 for the shafts 22, 50 23. The boxes for the shaft 23 rest on the bottom walls of the openings 34. The boxes 35 for the shaft 22 are preferably supported on the lower ends of vertically slidable rods 36, whereby the shaft 22 may be raised and lowered, at will, 55 to permit the strips *a* to be inserted between the pairs of edging elements 20 when the apparatus is to be set in operation. The lower end of each rod 36 is provided with a head 37 fitting into a recess formed in a block 38 which is suitably se- 60 cured to the adjacent bearing box 35. The rod 36 slides endwise in and extends through a tubular member 39 adjustably mounted in a bridge 40 seated on the upper end of the adjacent standard. The tubular member 39 is preferably 65 formed integrally with a casing 39a on which is mounted a cylinder 41 enclosing a piston 41a. Between each piston rod and upper end of the adjacent rod 36 is provided a toggle 42, so that when the piston 41a is in one position it acts 70 through the toggle 42 to move the adjacent rod downwardly and when the piston 41a is moved to its other position the adjacent rod 36 is moved upwardly. The pistons 41a are operated by a suitable fluid under pressure supplied to the outer or inner sides of the pistons by pipes 43. 75

The supply of the fluid through the pipes 43 is controlled by a suitable valve (not shown) to control the movement of the pistons in the proper direction simultaneously (toward or away from each other in the present disclosure—see Fig. 3), whereby the shaft 22 is bodily raised or lowered. The tubular members 39 are adjustably mounted in the bridges 40, so that when the shaft 22 is moved downwardly to its final position by the action of the toggles 42, the edging elements 20 will operatively engage the strips according to the predetermined width thereof. This adjustment of the members 39 is effected by providing screw threads on their outer walls and the walls of the openings through the bridges 40, the members being locked in adjusted position by upper and lower nuts 44 which are tightened on the members 39 against the opposite faces of the bridges 40. Provision is therefore made for adjusting or spacing the elements 20 according to varying widths of the strips *a*.

The elements 20 are mounted on each shaft 22, 23, in side by side relation between a fixed collar 22' adjacent one end of the shaft and a nut 22a threaded on a portion of the shaft near its other end, a spacer 45 being preferably provided between the nut 22a and the adjacent element 20. When found desirable, spacers may be provided between adjoining elements 20. The shafts 22, 23, extend through the bearing boxes 35, which are mounted in the standard 24, and carry on their outer ends worm gears 46, which mesh with worms 47 fixed to a driven shaft 48. At its lower end the shaft 48 is provided with a bevel gear 49 in mesh with a bevel gear 50, which is fixed to a shaft 51, the latter in turn being connected to and driven by the shaft of the motor 18.

The strip guiding elements forwardly of the strip edging means and the strip guiding elements rearwardly thereof, are similar in construction and therefore reference will be made to one such means, although corresponding parts are indicated by the same reference characters to insure a clear understanding of the construction, reference being made particularly to Figs. 4, 5, 6 and 7. 52 indicates a supplemental support which in this form of construction consists of a bar rigidly (but detachably) secured at its opposite ends to the opposed faces of the standards 24, 25, the detachment permitting the bar to be disconnected from the standard 25, when the latter is moved laterally, as shown in dotted lines in Fig. 3. The bar 52 is formed with front and rear slots 53 extending transversely to the feed of the strips *a* and each adjustably supports between its side walls a pair of guide devices 54 for one of the strips *a*, each guide device being adjustable independently of the other device of a pair and movable from end to end of the adjacent slot 53, whereby each pair of devices may be related to guide strips of different thicknesses and also related to any pair of edging grooves 21 formed in the edging elements 20. Each device 54 comprises the following: 55 indicates a shaft extending through the adjacent slot 53, the sides of the shaft throughout the height of the bar 52 being flattened (see Fig. 7) to slidably and non-rotatively engage the walls of the slot 53, whereby the shaft is held against turning. The upper end of the shaft 55 is provided with a bushing 56 having a flange at its lower end to engage the bar 52. A nut 57 threaded on the upper end of the shaft 55 and tightened through a washer 57a against the bushing in opposition

to the head 55a on the lower end of the shaft 55 serves to adjustably secure the shaft to the bar 52. 58 indicates a roller mounted to rotate on the bushing 56. By preference, the roller 58 is provided interiorly with a race for antifriction elements which engage therewith and the outer wall of the bushing 56. By providing each support 52 with two slots 53, the pairs of devices 54 may be positioned in staggered relation and thus permit the strips *a* to be guided in close relation and rectilinearly. This is advantageous where the strips are relatively narrow as it permits the over-all width of the machine to be reduced to a minimum and simplified.

As shown in Figs. 1 to 6, inclusive, the pairs of guide devices 54 forwardly of the edging elements turn or twist the strips *a* from the horizontal position as they pass the feed rolls 15, 16, to the vertical position and co-operate with the pairs of guide devices 54 rearwardly of the edging elements to guide and maintain the strips in spaced side by side or vertical positions for feeding to and between the edging elements; whereas the rolls of the mechanism 4, in the preferred form of construction, turn or twist the strips *a* in the reverse direction to a horizontal position, for feeding to the coiling mechanism 5 and to permit treatment of the strip edges when desired, as hereinafter set forth.

The mechanism 4 may be similar in construction to the mechanism 2 where further treatment of the strip edges is not necessary.

If desired, the strips *a* may be delivered direct from the edging mechanism to suitable coiling drums, but by preference they are returned to the horizontal position and in a common plane so as to be coiled simultaneously on a single drum.

In the present disclosure the mechanism 4 is constructed to effect feeding of the strips *a* and is also constructed to effect further treatment thereof, namely, to roll down the up-set edges of the strips, as shown in Figs. 14, 15 and 16. Referring to these views, 59, 59, indicate standards mounted on the support 13 and formed with openings 60 to receive and support pairs of bearing boxes 61, 62, the boxes 61 serving to support a pair of roll-down rolls 63 and the boxes 62 serving to support a pair of back-up rolls 64. The boxes 61 are permitted to float in the openings 34 so that the rolls 63 are free to be acted upon by the rolls 64. The boxes for the lower roll 64 rest on the bottoms of the openings 60 so that this roll is stationarily supported, whereas the upper back-up roll 64 is supported in a predetermined fixed position relative to the lower back-up roll 64, by screws 65 adjustably mounted in bridges 66 and provided with heads 67 fitting recesses in blocks 68 suitably secured to the adjacent boxes 62. In this arrangement, the rolls 64 are spaced so that the strips *a* may pass between the rolls 63 and the latter, by reason of the engagement of the rolls 64 therewith will roll down the upset edges of the strips to the planes of their opposite faces, as shown in Fig. 15. As the rolls 64 are power driven, the friction between them and the rolls 63 will serve to rotate the latter. The driving means for rolls 64 consist in extending their supporting shafts beyond one of the standards 59 and providing on such extended ends worm wheels 69 which mesh with worms 69a on a shaft 70, the latter being driven through gearing in a casing 71 by the shaft 51.

72 indicates uprights disposed forwardly and rearwardly of the mechanism 3 and supporting the inner ends of platforms 73 which extend

between the mechanism 3 and mechanisms 2 and 4, the outer ends of the platforms being secured to angles 74, mounted on the adjacent standards. The platforms 73 support the strips *a* when being positioned between the edging elements and the rolling down rolls 63.

Figs. 8 to 13, inclusive, illustrate a modified form of construction wherein each guide means for all of the strips forwardly and rearwardly of the edging mechanism 3 is mounted on the support 13 so that the standard 25 may be moved independently of the guide means and their supports, and supplemental means, indicated as an entirety at 75 are provided for guiding the strips 15 as they pass between the pairs of edging elements 20.

Referring to these figures, 76 indicates inverted substantially U-shaped members forwardly and rearwardly of the edging mechanism 3, the legs 20 of each member being provided with flanges 76^a which are secured to the support 13 by bolts 76^b.

The legs of each member 76 are connected by (a) a crossplate 78 on which are adjustably mounted pairs of guide devices 54, the latter being preferably similar in construction and similarly mounted to the guide devices already referred to, and (b) a cross support 79, the purpose of which will later appear. As shown in Figs. 8 and 9, we form in the plate 78 a third slot 53' in 30 which are supported the shafts of auxiliary guide devices 54', one for each inner pair of guide devices 54, except the center pair. Each auxiliary device 54' is similar in construction to each of the devices 54 and co-operates with the adjacent inner pair of devices 54 to prevent contact of the strip *a* guided by said inner pair of devices with the adjacent outer pair of devices 54. This construction incorporating the auxiliary guide devices 54' is advantageous where the stock A is slotted into strips *a* that have a width less than the distance or space between the related sets of grooves 21 and the outer strips have to be laterally separated for alignment with the edging grooves 21.

45 Of the supplemental guide means 75, 80, 80' indicate pairs of brackets, one for each set of edging elements 20, adjustably mounted on each cross support 79, and each pair of brackets on one support 79 aligned with the correspondingly 50 related pair of brackets on the other support 79. The brackets 80, 80', are independently adjustable transversely of the feed of the strips *a* on the supports 79, whereby guiding elements 81 supported by the brackets may be aligned with 55 the selected edging grooves 21 and also related to accommodate different thicknesses of the stock. To provide for this adjustment, each bracket is secured to the adjacent support 79 by a bolt 82, which extends through a slot 82' 60 formed therein, the slot being elongated as shown in Fig. 12.

The guide elements 81 comprise pairs of plates, one pair for each pair of brackets 80, 80', and the other pair of brackets 80, 80', aligned therewith, each plate of each pair being secured at its opposite ends to one bracket of one pair and the corresponding bracket of the other pair of brackets. As shown in Figs. 8, 10 and 12, the pairs of brackets 80, 80', related to each set of 70 edging elements support the adjacent pair of guiding plates 81 upon opposite sides of and in close relation to one of the strips *a* so as to guide the strip as it passes to and between the adjacent set of edging elements 20 and to prevent buckling 75 of the strip due to the pressure of these elements

upon the edges of the strip. In order that these functions of the plates 81 may be effective, the upper and lower edges thereof are disposed in planes within the peripheries of the elements 20 and beyond the opposite edges of the strips, but are cut away, as shown at 81' (see Figs. 11 and 13) so as to fit in close relation to such peripheries. The plates 81 are bolted to the brackets as shown in Figs. 11 and 12.

Each guide plate 81 preferably comprises upper and lower sections, the lower section being bolted to the adjacent brackets and the upper section being adjustably secured thereto for adjustment with the upper shaft 22 according to the width of the strips, this adjustment being provided for by forming vertical slots 83 in the brackets 80, 80' for the bolts that secure the upper section thereto.

In order that the plates 81 may be related to substantially the entire surfaces of the opposite faces of the strips *a*, and at the same time provide for the adjustment above referred to, the inner edges of the guide sections are provided with complementary edge portions which permit adjustment of the upper section without effecting a complete separation of the sections, so that under all conditions substantially the entire area of the strips are guided and danger of buckling thereof due to pressure of the edging or conditioning elements is avoided.

The coiling mechanism 5 comprises a drum 84, secured to a shaft which is mounted in a housing 85, the latter enclosing suitable driving mechanism and speed reducing gearing, driven by a motor 86. The coiling mechanism 5 may be of any desired construction, for example, such as shown in the co-pending application Serial No. 57,903 filed by Carl M. Yoder, one of the petitioners herein, now Letters Patent No. 2,116,057, dated May 3, 1938. In coiling the strips they may, if desired, be fed to and coiled on two or more drums.

From the foregoing description it will be noted that our invention adapts itself to the edging or conditioning of strips that are relatively narrow. The strips are fed in side by side relation, with their surfaces parallelly related, in a common plane, so that the edging elements for all of the strips may be mounted on a pair of shafts, thereby materially simplifying the construction, while providing for simultaneous treatment of all the strips.

From the foregoing description it will also be noted that sheet stock of any desired width and/or of indefinite length may be supplied to the trimming and slitting mechanism and fed forward by it or other feeding mechanism, the strips separately turned longitudinally at an angle for engagement with the edging elements and then by preference turned into a common plane for coiling.

In the present disclosure, the stock is fed in a horizontal plane and trimmed and slitted into strips, which are then separately turned into a right angle position and edge conditioned and thereafter returned to the horizontal position. In this process and arrangement, the machine is of a simplified character, has large capacity and provision is readily made for providing variously shaped or conditioned edges on the strips.

To those skilled in the art to which our invention relates, many changes in construction and widely differing embodiments and applications of the invention will suggest themselves without departing from the spirit and scope of the invention.

tion. Our disclosures and the description herein are purely illustrative and not intended to be in any sense limiting.

What we claim is:

- 5 1. In apparatus of the class described, the combination of means for supplying sheet metal stock, mechanism for slitting the stock longitudinally into strips, a pair of driven rolls for feeding the strips in substantially edge to edge relation, sets 10 of edging elements, one set for each strip, mechanism between said pair of feed rolls and said sets of edging elements for separately turning the strips longitudinally into an angular position, said turning mechanism being adjustable transversely to the direction of feed of the strips and operating to guide the strips to the respective related grooves formed in said sets of edging elements, guide means on that side of said sets of edging elements remote from said turning mechanism, a pair of driven feed rolls co-operating with said guide means for turning the strips longitudinally into substantially edge to edge relation for feeding thereby, and means for 15 coiling the strips. 20
- 15 2. The herein disclosed process which consists in continuously feeding sheet metal and longitudinally slitting the sheet metal into strips, simultaneously turning the strips about substantially longitudinal axes into an angular position, then conditioning the opposite side edges of the strips, then turning the strips about substantially longitudinal axes into a common plane and feeding them to a supporting means. 25
- 20 3. The herein disclosed process which consists in continuously feeding sheet metal and longitudinally slitting the sheet metal into strips, simultaneously turning the strips about substantially longitudinal axes into an angular position, then conditioning the opposite edges of the strips, then turning the strips about substantially longitudinal axes into a common plane and feeding them longitudinally, and then coiling the strips. 30
- 25 4. The herein disclosed process which consists in continuously feeding sheet metal and longitudinally slitting the sheet metal into strips, simultaneously turning the strips about substantially longitudinal axes into an angular position, then conditioning the opposite edges of the strips, then turning the strips about substantially longitudinal axes into a common plane and feeding them longitudinally, and then coiling the strips.

CARL M. YODER.
PAUL J. ABEL.
